United States Patent Office.

OLNEY CHURCHILL, OF CANTON, PENNSYLVANIA.

Letters Patent No. 74,894, dated February 25, 1868.

IMPROVEMENT IN CARRIAGE-JACKS.

The Schedule referred to in these Letters Patent and making part of the same.

TO ALL WHOM IT MAY CONCERN:

Be it known that I, OLNEY CHURCHILL, of Canton, in the county of Bradford, and State of Pennsylvania, have invented certain new and useful Improvements in Lever-Jacks for Wagons or Carriages; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in a novel construction of a lever-jack, for use in connection with wagons or carriages, whereby I am enabled to produce a very cheap, simple, and efficient article.

Figure 1 is a vertical section taken on the line $z z$ of fig. 2.

Figure 2, a horizontal section taken on the line $z z$ of fig. 1.

Figures 3 and 4 represent a modification of the same.

In constructing my improved device, I take a small wooden bar, B, and form in its front side, either by cutting away a portion, or by fastening narrow strips on the front at each edge, a flat groove, to receive a strap, b, and in the upper end of this bar, I journal or mount a pulley, a, which should be equal in width to the strap, the lower end being secured to a small block or piece of plank, A, to form a base to support the apparatus, and prevent it from sinking into the ground, when supporting the weight of the wagon or other vehicle, as represented in fig. 1. I then provide another bar, C, and placing it upright against the front face of the bar B, enclose it by a metal clasp, c, which is secured rigidly to the bar B, near its upper end, as shown in figs. 1 and 2, the bar C sliding loosely up and down in the clasp c. I provide a strong strap, b, and attach one end securely to the back side of the bar C near its lower end, and pass its opposite end up over the pulley a, and down a short distance on the rear side of bar B, and attach to its end a ring, o, of proper size to encircle and slip easily on a lever, L, as represented in fig. 1, this lever being provided with one or more notches or projections, to prevent the ring o from slipping when the lever is inclined, as shown in fig. 1. In the bar B, I bore a series of holes, e, of proper size to permit the end of the lever L to be inserted therein, and hold the same rigidly in position, when shoved fairly in, or, if preferred, the front bar C may be made somewhat wider than the bar B, as represented in fig. 4, which is a top plan view, the clasp c being slightly changed in form, as there represented, to correspond. A series of notches may then be cut in the projecting edge of the bar C, and a pawl, n, pivoted to the side of bar B, so as to engage in the notches, when the bar C is raised, and thus hold it up, as represented in fig. 3, which is a side elevation, representing this modification.

To use my improved jack it is placed in position, and the upper end of bar C placed under the axle of the wagon or carriage. The lever L is then slipped into the ring o, and its outer end is raised until its opposite end will enter one of the holes e a short distance, when its outer end is depressed, thereby drawing the strap b down over the pulley a, whereby the bar C, with the axle resting on it, is elevated, and when the lever is brought to a horizontal position, as indicated by the red lines in fig. 1, it is shoved entirely into the hole e, which then holds it securely in place. If the pawl n be used, then the shoving of the lever L into the hole for the purpose of locking it in position may be omitted, if desired.

When not in use, the lever L is removed from the ring, and its end inserted in a hole bored in the front part of the base, A, as indicated in red in fig. 1, and the bar C being shoved down, the whole is then in a compact form, occupying but little space, and can be readily stored under the seat, and carried with the vehicle, for use on the journey, if desired. Being composed of wood, it is unusually light, and hence is more convenient for use or transportation, than the ordinary articles of its kind, especially when made of metal.

Having thus described my invention, what I claim, is—

A lever-jack, when constructed and operating substantially as shown and described.

OLNEY CHURCHILL.
